L. S. WELLS

MEANS FOR HEATING RAILWAY RAILS AND THE LIKE

Filed March 22, 1922

UNITED STATES PATENT OFFICE.

LOREN S. WELLS, OF NEW YORK, N. Y.

MEANS FOR HEATING RAILWAY RAILS AND THE LIKE.

Application filed March 22, 1922. Serial No. 545,635.

To all whom it may concern:

Be it known that I, LOREN S. WELLS, a citizen of the United States, and resident of New York city, borough of Manhattan, in the county of New York and State of New York, have invented certain new and useful Improvements in Means for Heating Railway Rails and the like, of which the following is a specification.

10 On electrified railroads the power for traction purposes is delivered to cars or trains by means of an electrical conductor commonly called third rail, channel rail and other forms which parallel the track rails.

15 The power to operate cars or trains is collected from such conductors by means of shoes attached to the cars which come in contact with the stationary electrical conductor referred to. During time of sleet or 20 snow storms a coating of ice frequently forms on the conductor rails which insulates them electrically from the shoe or other form of collector on the car, thereby preventing, temporarily at least, the collection of power 25 for the operation of the car and seriously interfering with the train schedule, the shoe being electrically connected with the motor equipments on the cars, etc.

The object of my invention is to provide 30 simple and effective means in conjunction with railway rails or conductors, and particularly in association with the third rail or other rails that conduct the current for the motors of the railway cars, to prevent 35 formation or accumulation of sleet, snow, or ice on such rail or conductor, which heating means will not interfere with the operation of the railroad trains, and will not be liable to be injured or to permit leakage of electric current.

My invention comprises novel details of improvement that will be more fully hereinafter set forth, and then pointed out in the claims.

45 Reference is to be had to the accompanying drawings, forming part hereof, wherein—

Figure 1 is a side view illustrating my improvement in connection with a so-called 50 third rail of a railway track;

Fig. 2 is an enlarged detail view adjacent to the joint between two rails;

Fig. 3 is a section on line 3, 3, in Fig. 2;

Fig. 4 is an enlarged detail section illustrating connecting means between conductors;

Fig. 5 is a detail perspective view illustrating supporting means for conductors along the rail;

Fig. 6 is a partly sectional detail view 60 illustrating the conductor protector;

Fig. 7 is an end view of Fig. 6, and

Fig. 8 illustrates protecting boards along the rail.

Similar numerals of reference indicate 65 corresponding parts in the several views.

The numeral 1 indicates a part to be heated, such as a railway rail, or a conductor or power line for an electrically propelled railway, such as commonly called 70 third rail, channel rail, or other form of conductor which parallel the railroad track rails, and from which power to operate the trains is collected by means of shoes on a car which come in contact with such electrical 75 conductor. At 2 is an electrical conductor to supply heat to the rail or conductor 1, the conductor 2 being shown located along one side of rail or conductor 1 and maintained in thermal relation thereto, so that the heat 80 from the resistance conductor 2 will radiate to rail or conductor 1 to heat the latter. Conductor 2 is shown, in part, covered by refractory heat conducting means, such as insulating sleeves or tubes 3, which may be 85 in the nature of porcelain, mica, asbestos, or other insulating tubes, strung along conductor 2, preferably in relatively close relation. The resistance conductor with its insulating heat conducting material thereon 90 is shown enclosed within a moulding 4, shown in the form of a channel piece, which may be of metal, having one side open, the open side thereof being located against the web 1^a of conductor or rail 1, so that the 95 heat from conductor 2 will readily radiate to rail 1. The moulding 4 is preferably provided with an insulating lining 4^a, shown open on the side opposite rail 1. The moulding 4 extends along the rail to protect conductor 2 and is shown retained in place by means of spaced blocks 5, which may be of wood, having lateral recesses 6 receiving the moulding 4. The blocks 5 are retained against the conductor rail 1 100 by means of clips 7. The clips 7 are shown in the form of metal strips having a main portion 7^a adapted to bear against the bottom of the rail and at one end having a reverse hook-like portion at 7^b to engage 105 the adjacent edge of the bottom web of the rail, or a block 5' as in Fig. 8, the opposite

110

end of clip 7 having a prong or projection 7^b adapted to fit over and against the adjacent lower portion of block 5. By preference the block 5 has an angular base portion 5^a to fit against the corresponding portion of the base web of rail 1, and the block is provided with a recess 5^b at its lower portion on the exterior to receive the prong 7^b, whereby the block is retained against the rail and lateral shifting of the block along the rail is prevented. After the block 5 has been located against the rail the end 7^b of clip 7 is to be hooked against the rail and the prong 7^b bent into the recess 5^b, or the end 7^b is engaged with block 5' in case that is used as in Fig. 8. The blocks 5 are to be secured along the rail in any desired spaced relation to maintain the moulding 4 and the contained conductor 2 in proper position below the tread of rail 1. At the junction between two rails 1, such as adjacent to the fish plate 8, the conductor and moulding 4 may extend, or an insulated conductor 9 may be provided to span the fish plate, the ends of the conductor 9 being electrically and mechanically connected to the adjacent ends of resistance conductors 2 that extend along the corresponding rails 1. As a convenient means for such connection a connector 10 is shown comprising a well known form of metal tubing having screws 11 to secure the inserted ends of the conductors 2 and 9, (Fig. 4). Such connector 10 is preferably enclosed within an insulator 12, which may be of porcelain or other suitable insulating material. The inner end of insulator 12 and the adjacent end of moulding 4 are shown abutting and enclosed within the recess 6 of the corresponding block 5, whereby said parts are united and maintained against rail 1 (see Fig. 2).

By providing the resistance conductor 2 with insulators 3 strung along the conductor, I am enabled to use refractory insulating means through which heat from the resistance conductor may radiate without injury to the insulation due to vibration or bending of rails or weather conditions, since my improvements not only may be used to heat conductor rails, such as third rails, but may also be applied along the track rails, particularly at the places where switches, frogs, and the like are located, to prevent the accumulation of snow, ice and sleet thereon. To limit the movement of the insulators 3 and 12 due to their expansion from heat within moulding 4 I provide stops 15 at one or both ends of a moulding to abut the endmost insulator, the stops being apertured at 15° for the conductor 2, (Figs. 6 and 7). The flexible insulated conductors 9, which span the fish plates, are not required as heating elements, since when

the main portions of the conductor rail are kept heated the car motor shoes will ordinarily slide over the rails at their joints without stalling the train, because the rails on opposite sides of the fish plate will be free from sleet, snow and ice and the heat in rails 1 is carried along to their ends.

To protect the conductors 2 from snow, sleet and ice boards 14 may be placed along the sides of the rails outside of the moulding 4, below the rail treads, and secured to the blocks 5, as by nails or screws 5^d, see Fig. 8. The blocks 5' on the sides of the rails opposite the blocks 5 afford means to secure boards 14' along the rails below their treads similarly to that described respecting boards 14. Said boards being outside of the conductors resist outward radiation of heat therefrom and drive the heat toward the rail.

By the term rail as used by me I mean to include railway rails whether used as conductors of electricity, such as so-called third-rails, channel rails and rails, or as track rails, as well as other forms of electrical conductors that it is desired to maintain, at least temporarily, at a temperature above atmosphere.

Having now described my invention, what I claim is:

1. Means for heating rails comprising a resistance conductor extending along the rail, spaced blocks retaining the resistance conductor, means to secure the blocks to the rail, and a board secured along the rail outside of said conductor to resist radiation of heat therefrom and drive the heat toward the rail.
2. Means for heating rails comprising a resistance conductor extending along the rail, a moulding enclosing the resistance conductor and having one side free to permit radiation of heat therethrough to the rail, spaced blocks retaining the moulding adjacent to the rail, and means to retain the blocks.
3. Means for heating rails comprising a resistance conductor extending along the rail, heat conducting electrical insulators upon the resistance conductor, a moulding enclosing the resistance conductor, said moulding having one side open opposing the rail, and means to retain the moulding along the rail.
4. Means for heating rails comprising resistance conductors extending along the rails, an insulated conductor attached to the resistance conductors, insulators enclosing the junction between said conductors, blocks retaining said insulators, and means to retain the blocks adjacent to the rail.
5. Means for heating rails comprising resistance conductors extending along the rails, insulated conductors attached to the resistance conductors, insulators enclosing

the junction between said conductors, moulding enclosing the resistance conductors, blocks retaining the adjacent portions of said insulators and said moulding, and means to retain the block adjacent to the rail.

6. The combination of a rail, a resistance conductor at a side of the rail, a molding having one side open opposing the rail and enclosing said conductor, blocks spaced along the rail having recesses facing the rail and receiving said conductor and molding, and means to retain said blocks against the rail.

7. The combination of a rail, a resistance conductor at a side of the rail, blocks spaced along the rail having recesses receiving said conductor, and clips having hook-like portions fitted against the rail and having prongs retaining the blocks against the rail.

8. The combination of a rail, a resistance conductor at a side of the rail, blocks spaced along the rail having recesses receiving said conductor, and clips having hooklike portions fitted against the base of the rail and having prongs retaining the blocks against the rail, said blocks having recesses receiving said prongs for retaining the blocks from displacement along the rail.

9. Means for heating rails comprising a resistance conductor extending along the rail, an insulated conductor attached to the resistance conductor, an insulator enclosing the junction between said conductors, a moulding enclosing the resistance conductor, said moulding having one side open opposing the rail to permit the passage of heat from the resistance conductor to the rail, a block having a recess receiving adjacent portions of the insulator and moulding, and means to retain the block adjacent to the rail.

10. Means for heating rails comprising a resistance conductor extending along the rail, an insulated conductor attached to the resistance conductor, an insulator enclosing the junction between said conductors, a moulding enclosing the resistance conductor, said moulding having one side open opposing the rail to permit the passage of heat from the resistance conductor to the rail, a block having a recess receiving adjacent portions of the insulator and moulding, and means to retain the block adjacent to the rail, said resistance conductor

having electrical insulating heat conducting sleeves thereon enclosed in said moulding.

11. The combination of rails, fish plates connecting them, resistance conductors along the rails, insulated conductors along the fish plates connected to the resistance conductors, moulding enclosing the resistance conductors, insulators enclosing the junction between the conductors, blocks retaining the moulding and insulators adjacent to the rails, and means retaining the blocks adjacent to rails.

12. Means for heating rails comprising a resistance conductor extending along the rail, separate heat conducting electrical insulators upon the resistance conductor, a moulding enclosing the resistance conductor and the insulators, and stops at the ends of the moulding to limit movement of the insulators along the conductor.

13. Means for heating rails comprising a resistance conductor extending along the rail, separate heat conducting electrical insulators upon the resistance conductor, a moulding enclosing the resistance conductor and the insulators, and stops at the ends of the moulding to limit movement of the insulators along the conductor, said stops having openings receiving the resistance conductor.

14. Means for heating rails comprising a resistance conductor extending along the rail and having a heat conducting covering, a moulding extending along the rail enclosing said conductor and having one side opposing the rail free for radiation of heat from the conductor to the rail, and a lining, of insulating material within the moulding outside of the conductor and open on the side toward the rail.

15. Means for heating rails comprising a resistance conductor extending along the rail and having a heat conducting covering, a moulding extending along the rail enclosing said conductor and having one side opposing the rail open for radiation of heat to the rail, an insulating lining within the moulding above, below and outside of said conductor and open on the side toward the rail.

Signed at New York city, in the county of New York, and State of New York, this 20th day of March, A. D. 1922.

LOREN S. WELLS.
